UNITED STATES PATENT OFFICE.

ALFRED MARTIN BERRY, OF WOODHAVEN, NEW YORK, ASSIGNOR TO INTERTYPE CORPORATION, OF BROOKLYN, NEW YORK, A CORPORATION OF NEW YORK.

CHANNEL-ENTRANCE FOR TYPOGRAPHICAL MACHINES.

1,349,488.

Specification of Letters Patent. Patented Aug. 10, 1920.

Application filed September 23, 1919. Serial No. 325,705.

To all whom it may concern:

Be it known that I, ALFRED M. BERRY, a citizen of the United States, residing at Woodhaven, in the county of Queens and 5 State of New York, have invented new and useful Improvements in Channel-Entrances for Typographical Machines, of which the following is a specification.

The present invention relates to improvements in typographical machines and more especially to those of the linotype class employing circulating matrices which are returned, after use, through a distributor to the upper end of the magazine. The primary object of the invention is to provide a novel and improved channel entrance for guiding the matrices while passing from the distributor to the magazine, this channel entrance, according to the present invention, 10 being capable of accommodating itself to the usual or relatively thin matrices and also to very thick matrices, such, for example, as those used for display and advertising work, the channel entrance thus insuring correct entrance of the relatively thin 15 matrices into the respective channels of their magazine even though the same channel entrance is used for the guiding of thick matrices into their magazine.

To this end the invention consists in certain improvements and combinations and arrangements of parts all as will be herein-after more fully described, the features of novelty being pointed out particularly in 20 the claims at the end of the specification.

In the accompanying drawing:—

Figure 1 is a perspective view, partly in section, showing the upper corner of a magazine and a part of a channel entrance embodying the present invention.

Fig. 2 is a detail perspective view of one of the channel entrance partitions.

Fig. 3 represents an end elevation of the distributor, the upper portion of the magazine and the interposed channel entrance.

Fig. 4 is a view of a portion of the magazine looking down upon the top thereof.

Fig. 5 is a collective view showing thick and thin matrices capable of being handled 25 by the channel entrance.

Similar parts are designated by the same reference characters in the several views.

The invention, in the present instance, is shown applied to a typographical machine

of the linotype class, *a* representing the distributor bar along which the matrices are conveyed in the usual way by the distributor screws *B*, *C* designates the channel entrance which embodies suitably spaced partitions *C'*, the matrices, dropping at appropriate points from the distributor bar, being received in the spaces between the partitions of the channel entrance, the partitions being maintained in correct relative position by the curved rear plate *C²* and the front plate *C³*, and *D* designates the upper portion of the magazine, the magazine being composed of a pair of upper and lower plates *D'* which are formed on their inner faces with grooves *D²* in which the lugs or ears *M'* of the matrices *M* are adapted to travel and the upper ends of these grooves *D²* are beveled or widened as at *D³* to facilitate the entrance of the lugs or ears *M'* of the matrices into the channels *D²* to which these beveled portions lead.

Heretofore, typographical machines of this class have been limited to the use of relatively thin matrices bearing relatively small type characters on their edges. Recent developments, however, demand the use of thick matrices bearing relatively large characters on their faces to be used for display and advertising work. The matrix *M* at the right of Fig. 5, for example, shows a relatively thin matrix such as those heretofore used generally, and the matrix at the left of said figure represents a relatively thick matrix such as those used for display and advertising printing. The present invention enables the same machine to use not only the usual or relatively thin matrices, but to also use the relatively thick ones and this increase in the capacity of the machine is attained without impairing the certainty and facility of operation of the machine in the handling of the usual or thin matrices. In order to enable the machine to use the thick matrices, it is necessary to space the partitions *C'* of the channel entrance more widely than heretofore in order to permit the passage of the thick matrices, and means is provided whereby when the magazine containing the thick matrices is replaced by one containing the usual or thin matrices, these thin matrices will be so guided by the channel entrances that they will enter directly and with certainty the respective matrix

guiding channels in the magazine. Preferably and as shown in the present instance, the channel entrance is provided with means which will accommodate itself automatically to the thickness of the matrix being handled, such means comprising a blade, flexible member, or additional partition piece C^4 which is fixed at or toward its upper end to the partition C' while its lower end may be flexed or is movable laterally in a direction toward and from the side of the respective partition C' . This blade, member or partition piece C^4 is preferably made of very flexible material such, for example, as tempered spring steel or hard rolled bronze, the blade or member being of such thickness or strength that it will be deflected laterally or toward the partition C' to which it is attacked by the thick and consequently relatively heavy matrices during their descent without, however, retarding the speed of the descending matrices, and on the other hand, the thin and consequently relatively light matrices will be held upright by the flexible blade member or partition piece C^4 because the thin light matrices exert a very slight pressure tending to deflect the part C^4 and thus the thin and light matrices require only a slight force to maintain them in upright position. Preferably the blade, member or partition piece C^4 for each partition is so shaped and positioned that it closes the space between the respective adjacent partitions of the channel entrance except for a space that will permit the thinnest matrix to pass without deflecting the blade member or partition piece C^4 , the amount of deflection of the blade, member or partition piece C^4 by the relatively thicker matrices being in proportion to the thicknesses of such matrices.

The present invention enables the usual relatively thin matrices and also the thick matrices to be used efficiently and satisfactorily in the same machine. If the spaces between the partitions C' of the channel entrance were merely widened to permit the passage of the thick matrices, difficulties would result in the handling of the usual or relatively thin matrices because these thin matrices would become tilted in the wide spaces between the partitions and when they reached the magazine they would not properly enter the matrix guiding channels D^2 . Fig. 4 shows the position in which a relatively thin matrix would be presented to the magazine if merely the spaces between the partitions of the channel entrance were widened. The present invention, however, provides means which insures the maintenance of the matrices in upright position, notwithstanding the varying thicknesses of the matrices and hence correct entrance of the matrices into the magazine is insured. The means provided by the pres-

ent invention for accomplishing this result is self-adjusting, that is to say, the channel entrance accommodates itself to the thicknesses of the matrices being handled and hence manual adjustment of the channel entrance for the different thicknesses of the matrices handled is unnecessary.

What is claimed is:—

1. In a typographical machine of the class embodying a distributor for returning the matrices to the appropriate channels of a magazine, resilient means to automatically direct all matrices in their passage from the distributor to the appropriate channels in the magazine.

2. In a typographical machine of the class embodying a distributor for returning matrices to the appropriate channels of a magazine through a channel entrance provided with spaced partitions forming matrix-directing passages, interference means projecting from said partitions and into the respective matrix directing passages and operative to direct matrices of varying thickness and belonging to different fonts to one side of the respective matrix passages.

3. In a typographical machine of the class embodying a distributor, a magazine to receive matrices therefrom, and a channel entrance forming passages for guiding the matrices while passing from the distributor to the magazine, means within said channel entrance capable of yielding laterally of the respective matrix guiding passages, under the influence of the passing matrices, to accommodate the matrix guiding passages to matrices of different thicknesses.

4. In a typographical machine of the class described, the combination with a distributor, a magazine to receive matrices therefrom, and a channel entrance having spaced partitions forming a passage between them through which matrices are adapted to pass from the distributor to the channels for the respective character bearing matrices in the magazine, of a guide projecting from one of said partitions laterally into said passage and adjustable automatically by a passing matrix for determining the width of the matrix passage in accordance with the width of the passing matrix.

5. In a typographical machine, a channel entrance for guiding the matrices while passing from the distributor to the magazine, said channel entrance having spaced partitions for the passage of the matrices between them, and resilient means projecting into the space between adjacent partitions for a distance which is determined automatically by and according to the thickness of a passing matrix.

6. In a typographical machine, a channel entrance for guiding the matrices while passing from the distributor to the magazine, said channel entrance having spaced parti-

tions for the passage of the matrices between them, and a resilient guiding member projecting into the space between adjacent partitions to engage a side of a passing matrix, said guiding member being movable laterally in said space by a passing matrix to an extent determined by the thickness of such passing matrix.

7. In a typographical machine, a channel entrance for guiding the matrices while passing from the distributer to the magazine, said channel entrance having partitions to form matrix passages between them, and a resilient matrix guiding member in each passage projecting from one partition toward the adjacent partition and capable of being deflected laterally across such passage by a passing matrix to an extent determined by the thickness of such matrix.

8. In a typographical machine, a channel entrance for guiding the matrices while passing from the distributer to the magazine, said channel entrance having partitions to form matrix passages between them, and a

resilient matrix guiding member projecting into such passage and capable of deflection by a passing matrix to accommodate the width of such passage automatically to matrices of different thicknesses.

9. In a typographical machine, a channel entrance for guiding the matrices while passing from the distributer to the magazine, said channel entrance having partitions to form matrix passages between them, and a flat flexible blade fixed toward its upper end to the side of a respective partition and having its lower end projecting into the matrix passage, the lower end of said blade being movable laterally of the matrix passage by a passing matrix.

In testimony whereof I have hereunto set my hand in presence of two subscribing witnesses.

ALFRED MARTIN BERRY.
